UNITED STATES PATENT OFFICE.

WILLIAM H. M. ZSCHIESCHE, OF BARTLETT, TEXAS.

CORN-POPPER.

1,222,511.

Specification of Letters Patent. Patented Apr. 10, 1917.

Application filed March 31, 1916. Serial No. 88,008.

To all whom it may concern:

Be it known that I, WILLIAM H. M. ZSCHIESCHE, a citizen of the United States, residing at Bartlett, in the county of Bell 5 and State of Texas, have invented certain new and useful Improvements in Corn-Poppers; and I do hereby declare the following to be a full, clear, and exact description of the invention, such as will enable 10 others skilled in the art to which it appertains to make and use the same.

This invention relates to new and useful improvements in a corn popper and one of its objects is the provision of a device of this 15 character, which shall be simple, durable and efficient, and which may be manufactured and sold at a comparatively low cost.

Another object of this invention is to provide a receptacle, having an agitating blade 20 rotatably mounted therein and adapted to be operatively connected to a cover, whereby upon turning of the cover, the agitating blade will be rotated to prevent corn within the receptacle from burning.

25 A further object of this invention is to provide a vertically extending standard secured centrally of the receptacle to rotatably support the agitating blade and the cover and which will support the cover in spaced relation to the top edge of the receptacle, whereby said cover may be readily rotated to rotate the agitating blade.

With these and other objects in view as will become more apparent as the description 35 proceeds, the invention consists in certain novel features of construction, combination and arrangement of parts as will be hereinafter more fully described and claimed.

40 For a complete understanding of my invention, reference is to be had to the following description, and accompanying drawing, in which:—

45 Figure 1 is a vertical sectional view of a corn popper, constructed in accordance with my invention,

Fig. 2 is a longitudinal sectional view of the same, taken on the line 2—2 of Fig. 1, and

50 Fig. 3 is a perspective view of the agitating blade.

55 Referring in detail to the drawing, the numeral 1 indicates a receptacle consisting of a bottom 2, having upwardly and outwardly inclined walls 3 formed thereon to which a handle 4 is secured. A vertical

standard 5 is secured to the bottom 2 and centrally thereof and extends to a point above the top edge of the receptacle 1 to rotatably support an agitating blade 6. The 60 agitating blade 6 is provided with an opening intermediate its ends and has a collar 7 secured thereto in registration with the opening to receive the standard 5.

A cover 8 is provided with a central opening in which is secured a sleeve 9. The sleeve 9 extends to points above and below the cover 8 and is provided with its upper end closed by a curved wall 10. The sleeve 9 is adapted to receive the upper end of the 70 standard 5 and rest upon the upper end of the collar, the curved wall 10 resting upon the end of the standard, thereby supporting the cover 8 in spaced relation to the top edge of the receptacle. 75

Secured to the under face of the cover 8 adjacent the sleeve 9, is a pin 11, which is adapted to engage a horizontally disposed pin 12 carried by the upper end of the collar 7, whereby upon rotating the cover 8 80 by a handle 13, the agitating blade 6 will be rotated upon the standard 5.

In operation, pop corn is placed within the receptacle 1 and the cover 8 is placed upon the standard 5 and by rotating the 85 cover 8, the agitating blade 6 will be rotated and the corn will be kept from burning and sticking to the bottom of the receptacle.

While I have shown and described the preferred embodiment of my invention, it 90 will be understood that minor changes in construction, combination and arrangement of parts may be made without departing from the spirit and scope of the invention 95 as claimed.

Having thus described my invention, what I claim is:—

1. A corn popper comprising a receptacle, a handle secured to said receptacle, a vertical standard secured to the bottom of the receptacle, an agitating blade journaled on said standard, a cover journaled on the upper end of the standard, and means for connecting the cover to the agitator for rotating said agitator upon turning of the 100 cover. 105

2. A corn popper comprising a receptacle, a handle secured to said receptacle, a standard secured to the bottom of the receptacle and extending to a point above the top edges thereof, an agitating blade provided with an opening intermediate its ends to re- 110

ceive the standard, a collar secured to said agitating blade and surrounding the standard, a cover journaled on the upper end of the standard, and means for connecting the 5 cover to the collar for rotating the agitating blade upon turning of the cover.

3. A corn popper comprising a receptacle, a handle secured to said receptacle, a vertical standard secured to the bottom of the 10 receptacle and extending to a point beyond the top edge of the receptacle, an agitating blade provided with an opening intermediate its ends to receive the standard, a collar secured to the agitating blade and surrounding the standard, a cover, a sleeve secured centrally of the cover and receive the 15 upper end of the standard to rotatably support and relatively space the cover from the top edge of the receptacle, and means for connecting the cover to the collar for rotating the agitating blade upon turning of the 20 cover.

4. A corn popper comprising a receptacle, a handle secured to said receptacle, a standard secured to the bottom of the receptacle 25 and extending to a point above the upper edge of the receptacle, an agitating blade provided with an opening intermediate its ends to receive the standard, a collar secured to the agitating blade and surrounding the standard, a cover journaled on the upper end of the standard, a pin secured to the under face of the cover and extending downwardly therefrom, a horizontally disposed pin secured to the upper end of the 30 collar and adapted to be engaged by first mentioned pin for turning the agitating blade upon rotating the cover.

In testimony whereof I affix my signature in presence of two witnesses.

WILLIAM H. M. ZSCHIESCHE.
